Inventor:

Arthur Langerfeld.

UNITED STATES PATENT OFFICE.

ARTHUR LANGERFELD, OF NEW YORK, N. Y.

MEANS FOR EMBOSSED SHEET METAL.

SPECIFICATION forming part of Letters Patent No. 392,977, dated November 13, 1888.

Application filed July 9, 1887. Serial No. 243,886. (No model.)

To all whom it may concern:

Be it known that I, ARTHUR LANGERFELD, a citizen of the United States, residing at the city, county, and State of New York, have invented certain new and useful Improvements 5 in Embossing Sheet-Metal Articles; and I do hereby declare that the following is a full, clear, and exact description of the invention, which will enable others skilled in the art to 10 to which it appertains to make and use the same.

My invention relates to an improvement in the means for embossing spun bodies and other forms of sheet metal or other similar materials in dies by the pressure of a fluid, and is useful for 15 embossing vases, lamp-bodies, parts of chandeliers, silver and white-metal hollow ware; and the objects of my invention are to provide an expeditious means for placing the sheet metal in the die, making a tight connection with the 20 fluid, and readily disconnecting and taking out the sheet metal when embossed. I attain these objects by means of the device illustrated in the accompanying drawings, in which—

Figure 1 shows an external top view of an 25 inclosure, E G E G, containing the sections D of a sectional die, (shown in hatched lines,) and a sheet-metal body, B, already embossed, (shown in dotted lines,) and the tube T, with flange or plate F and flexible rim R, (shown in broken lines.) The dotted circle O is an opening in the body B. G G are bolts holding the inclosure E.

Fig. 2 shows a vertical section through the center, the same letters denoting the same parts 35 as in Fig. 1.

To carry out my invention, I close all openings or holes in the sheet metal B except the top opening, O, and insert into this opening O the flexible rim R. The flange or plate F 40 is made a little smaller than the opening O, so that it will pass through O and allow the flexible rim R to bend back and pass in also. The flexible rim R is firmly attached to the flange or plate F, and is made of rubber, leather, or 45 other suitable flexible material, and is large

enough to lap over onto the edge of the opening O of the sheet metal B. The body B is placed into a die consisting of sections D, having on the inside the desired embossed pattern sunk in reverse. This die is made of metal or 50 other sufficiently hard material in sections, where necessary to lift off, and is held together by a suitable inclosure, E G E G. The tube T, with flange or plate F, is kept in place either by being braced or held from without, or by 55 being inclosed in the inclosure E G E G, as shown. When so inserted and held, water or any other suitable fluid is forced into the body B through the tube T. The pressure against the flexible rim R will press it closely to the 60 edge O of the body B and form a tight joint or seal between the tube T and body B. The pressure of the fluid is raised high enough to cause the sheet metal B to yield and closely fill and conform to all the cavities on the inside 65 of the sections D of the die. The necessary pressure and time must be ascertained by experiment for each kind and thickness of sheet metal. The pressure is obtained by connecting the tube T with a force-pump or other 70 source giving a continuous very high pressure. When the pressure is taken off and the inclosure E G E G and sections D are removed, the tube T, together with the flange or plate F and rim R, can be as easily withdrawn as 75 they were inserted.

For some kinds of sheet metal which yield easier when hot it is of great advantage to use a hot fluid.

Having fully described my invention, what I 80 desire to claim and secure by Letters Patent is—

The combination of the die D, tube T, flange or plate F, and flexible rim R, substantially as shown, for the purpose specified.

ARTHUR LANGERFELD.
